EUGENE F. MITCHELL, OF SPOKANE, WASHINGTON.

FOLDING TABLE.

1,349,687.

Specification of Letters Patent. Patented Aug. 17, 1920.

Application filed June 9, 1919. Serial No. 302,869.

To all whom it may concern:

Be it known that I, EUGENE F. MITCHELL, a citizen of the United States, residing at Spokane, in the county of Spokane and State of Washington, have invented new and useful Improvements in Folding Tables, of which the following is a specification.

This invention relates to improvements in folding furniture.

One of the objects of this invention is to provide a folding table especially designed for outdoor camping use, and in this connection, it is a feature of this invention to provide such a table as can be not only folded up but also inclosed in a housing of such compact form that the latter may be readily seated on and carried by the running board of an automobile.

It is a further feature of this invention to provide housing sections constructed and arranged in such a novel manner that they will not only function as such, but will also function when unfolded, as a portion of the table top.

A further novel feature consists in providing one of the folding units to act as a container for dishes and like eating equipment, the container unit or section being proportioned and arranged to fit within and be inclosed by said housing sections when the latter are united in closed or folded relation.

A further novel feature consists in providing the container unit with a combined lid and leg supporting device, this device being embodied in a single structure adapted to function as a complete cover for the container when the structure is closed or folded, and also adapted to support the container in conjunction with other parts of the structure.

This invention has many other objects and features which will be more fully described in connection with the accompanying drawings and which will be more particularly pointed out in and by the appended claims.

In the drawings:—

Figure 1, is a plan view of my improved table structure unfolded to form a table.

Fig. 2, is a view in side elevation thereof.

Fig. 3, is a perspective view showing the table structure partially folded.

Fig. 4, is a perspective view showing the table structure completely folded.

Like characters of reference designate

similar parts throughout the different figures of the drawings.

As illustrated, 1 designates a housing table section united by hinges 2 with a companion housing and carrying section 3. The section 3 has a handle 4 similar to that employed on suitcases and grips, the ends being anchored by fittings 5. Such section 1 is provided at its free end with a pair of supporting legs 6 which are shown pivoted to said section at 7 and which are adapted to be folded into said section when the structure is closed. Structural provision is made for a slight endwise slant, of the legs 6, from the vertical, when said legs are in a supporting position, as clearly shown in Fig. 2. One element of a fastening device 8, is mounted on the end 9, or end wall 9, of section 1. Section 3 has supporting legs 10 which are likewise foldable into said section and I provide retaining bars 11 to hold said legs 10 in rigid relation with section 3. The bars 11 are pivoted to section 3 at 12, and the free ends of said bars are notched at 13 to be engaged with studs 14 on the legs 10. As a greater weight is supported by the legs 10 than by the legs 6, as will presently appear, this arrangement not only provides, with the canting of the legs 6, for rigidifying the support of the table but it also imposes the greater load on legs 10 squarely in the direction of their length. This arrangement permits of me making the legs 10 of lighter material although perhaps of better quality than legs 6.

When the sections 1 and 3 are unfolded and supported at their ends in a horizontal position, they are prevented from buckling or sagging intermediate of their length by the novel manner in which they are hingedly connected.

As will be seen by reference to Fig. 2, the axes or the pintles of the hinges 2 are near the lower margins of the sections 1 and 3 and the leaves 15 of said hinges are mounted upon the outsides of the adjacent walls of said sections. Above the hinges, metal abutments 16 are disposed, these abutments cooperating with the hinges to prevent the sections from sagging or buckling between their ends.

As will be clearly seen by reference to Fig. 3, the sections 1 and 3 are hollow sections, the back walls thereof forming the table when opened, and the hollow interiors thereof facing downwardly. Likewise, when

closed, the back walls and the edge walls contact to form the housing, and therefore I can finish the exteriors as desired and the finished areas will not only be uppermost and exposed when the table is opened, but they will be the only areas exposed when the table is closed.

The end or edge wall 17, of section 3, is shown separate from, but connected with said section by hinges having leaves 18 secured to the top of section 3 and leaves 19 secured to the exterior face of wall 17. In order to provide a tight fit, the edges of the section 3 are rabbeted, as indicated at 20 to fit within the edges 21, of section 1. Likewise the wall section 17 is similarly formed, as shown in Fig. 2. On the exterior of the end wall 17 is the companion member of the locking device which may be in the form of a loop catch 22 pivoted to a suitable fitting 23 and adapted to embrace the male member 8, as clearly shown in Fig. 4, when the sections are closed. This device may be additionally provided with a key-lock, if desired, the key-hole being indicated at 24.

Next referring to the improved container unit, as indicated at 25, the same consists of a rectangular box having a longitudinal dimension such as to permit it to be folded into section 3, as shown in Fig. 3, and having a transverse dimension sufficiently reduced with respect to section 3 to permit the legs 10 to be folded into section 3 in lateral relation to the container 25. The container has a bottom wall 26 and the opposite side of the container is open. The depth of the container is proportioned to fit snugly between the sections 1 and 3 when the latter are folded about said container so that the parts will not rattle. The walls 27, 28 and 29 of the container are suitably grooved to receive adjustable division boards 30, these boards being slidable into selected grooves to partition off the interior of the unit 25 as desired for the reception of dishes, knives and forks, and other utensils.

Said unit 25 is rigidly secured to the inside face of end wall 17, as clearly shown in Fig. 2 so that therefore the legs 10 will not only be called upon to support one end of the table proper but likewise a portion of the weight of the container 25. The container 25 is provided with a lid 31 which is hinged thereto at 32, the leaves 33 of the hinges being on the exterior of the cover 31 and the wall 28. The cover 31 is designed and proportioned to completely close the open top of the container 25 and I desirably provide hook eyes 34, on the cover, and hooks 35 on the side walls 27 whereby the cover may be fastened in a closed position while and after the structure is folded. It will be readily understood that in the absence of a cover, the loose equipment in

the container 25 would be liable to fall out of the same in the operation of folding up the structure. Furthermore, inasmuch as the partition walls of the container are removable, it is an easy matter to scour out the container and by having the lid, none of the contents of the container could soil the interior of the sections when the structure is folded.

On the inside face 36, of the lid 31, is pivoted at 37 an extension leg 38. When the cover is opened downwardly into a vertical position, as shown in Fig. 2, then the leg 38 will be swung on its pivot into projecting relation from the edge 39 to give the cover 31 the desired length to permit it to function as a supporting leg device for the free or outer end of the container 25. When the cover 31 is folded down onto the container to close the same, the leg 38 will be turned on its pivot so as to be disposed within the margins of the cover 31 to permit the latter to close down onto and be fastened to the container 25, as hereinbefore described.

By means of this container 25, supported in a horizontal and accessible position when the structure is open, it will be readily seen that the table portion proper, formed by sections 1 and 3, will be entirely free to receive the dishes and food set for each person without being encumbered by supply dishes or food to be later served. Thus the table portion proper has a service capacity or area greatly in excess of what it would otherwise have, with the same area, if it were not for the container 25. The container 25, in the open position shown, not only functions as a container for the dishes, but it may be additionally utilized as a serving table from which to serve food to the diners, it being readily obvious that boards similar to the division boards may be temporarily laid upon the tops of walls 27, 28 and 29.

After the cover 31 is closed, then the structure may be tilted over onto its side, as shown in Fig. 3, whereupon the container will be swung into section 3, likewise the legs 10. Legs 6 will then be swung into section 1 and thereupon section 1 will be turned into closed and edge-abutting relation against section 3, as shown in Fig. 4. The loop 22 having been fastened, the structure is adapted to be carried by the handle 4 in the manner of a suitcase.

A feature of novelty resides in the combination set forth in view of the fact that one of the locking devices is mounted upon the hinged wall 17, by reason of the fact that when the locking device 8 and 22 are closed, the wall 17 will be securely held closed without necessitating additional and special fastening means therefor which would otherwise be necessary.

It is believed that the novelty and utility

of my invention will be fully understood from the foregoing description, and while I have herein shown and described one specific form of my invention I do not wish to be limited thereto except for such limitations as the claims may import.

I claim:

1. In a folding table, hollow housing sections for inclosing the structure when folded and said sections being hingedly connected to support said sections from buckling between their ends from a horizontal position, legs for the ends of said sections for supporting said sections horizontally to form a table with the open portions of said sections downwardly disposed, a container having an open top and hinged to one end of one of said housing sections and proportioned to fit in and be inclosed by said housing sections when the latter are folded into a closed position, a container lid device hinged to that end of said container opposite the points of hinge connection of said container with its housing section and adapted to be adjusted downwardly to form a leg to support the free end of the container in a horizontal position.

2. In a folding table, hollow housing sections for inclosing the structure when folded and said sections being hinged to be closed about the structure or opened to form a table, legs for supporting said sections in an open position to form a table, a container hinged to one section, and a lid device for said container adapted to be adjusted into a supporting position to support the free end of said container.

3. In a folding table, hollow housing sections for inclosing the structure when folded, legs for supporting said sections in an open position to form a table, an extension unit hinged to one of said sections, and means hinged to said unit to support the latter in extension relation to said table sections, said extension unit being proportioned to fit in and be inclosed by said hol-

low sections when the latter are closed, and certain of said legs being foldable into said sections in lateral relation to said extension unit.

4. In a folding table structure, hollow housing sections for inclosing said structure when folded and adapted to form a table when opened, legs for supporting said sections to form a table, a container having an open top and being partitioned off on its interior to act as a receptacle, said container being hinged to one of said sections and adapted to be folded into the same, a lid for said container for closing the open top thereof, means for fastening said lid in closed relation onto said container to close the latter before the table is folded, said lid being adapted to be folded downwardly into a vertical position to act as a leg support for the free end of said container, and an extension leg mounted on said lid to engage the ground and coact with said lid to form an extension leg support therefor.

5. In a folding table structure, hollow housing sections for inclosing the structure when folded and said sections being hinged to each other to form a table when opened, legs for supporting said sections in their table adjustment, one wall of one section being hingedly connected thereto, an extension unit fixed to the inside face of said hinged wall, and a fastening device for locking said sections in closed relation, one member of said locking device being mounted on the outside face of said hinged wall and the other member of said locking device being mounted upon the remaining section, whereby said locking device will not only close the two sections but hold said hinged wall in closed relation against the section to which it is hinged.

In testimony that I claim the foregoing as my own, I hereby affix my signature.

EUGENE F. MITCHELL.
